US00D845197S

(12) **United States Design Patent** (10) Patent No.: **US D845,197 S**
(45) Date of Patent: **** Apr. 9, 2019**

(54) **CLUTCH PRESSURE PLATE COVER**

(71) Applicant: **Li Wang**, Shanghai (CN)

(72) Inventor: **Li Wang**, Shanghai (CN)

(73) Assignee: **Shanghai Engin Industry Co., Ltd**,
Shanghai (CN)

(**) Term: **15 Years**

(21) Appl. No.: **29/622,169**

(22) Filed: **Oct. 14, 2017**

(51) LOC (11) Cl. **12-16**

(52) U.S. Cl.

USPC **D12/180**

Primary Examiner — Kevin K Rudzinski

(57) **CLAIM**

I claim the ornamental design for a clutch pressure plate cover, as shown and described.

DESCRIPTION

FIG. 1 is a perspective view of a clutch pressure plate cover showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines and the interior surfaces adjacent to the circular broken lines present in FIG. 3 illustrate portions of the clutch pressure plate cover that form no part of the claimed design.

1 Claim, 7 Drawing Sheets
